UNITED STATES PATENT OFFICE.

HENRY D. ESTES, OF HARTFORD, KENTUCKY, ASSIGNOR OF ONE-FOURTH TO ROWAN HOLBROOK, ONE-FOURTH TO W. H. PARKS, AND ONE-HALF TO H. T. HOLBROOK, ALL OF HARTFORD, KENTUCKY.

PROPELLER.

1,220,080.

Specification of Letters Patent.

Patented Mar. 20, 1917.

Application filed April 20, 1916. Serial No. 92,463.

To all whom it may concern:

Be it known that I, HENRY D. ESTES, a citizen of the United States, residing at Hartford, in the county of Ohio and State 5 of Kentucky, have invented new and useful Improvements in Propellers, of which the following is a specification.

This invention relates to improvements in propellers for motor and power boats 10 and especially with reference to the provision of a propeller embodying blades which may be readily adjusted to any desired pitch and may be readily secured in position.

15 The object of the invention is to provide an improved propeller of this kind which can be adapted to the power and speed of the motor and secure the best possible results.

20 The invention consists in the features of construction, combination, and arrangement of devices, hereinafter fully described and claimed, reference being had to the accompanying drawings, in which:

25 Figure 1 is an elevation partly in section of an adjustable propeller constructed and arranged in accordance with my invention.

Fig. 2 is a side elevation of the same.

Fig. 3 is a detail sectional view on the 30 plane indicated by the line *a—a* of Fig. 1.

My improved propeller comprises a hub 1 and a suitable number of adjustable blades 2. As here shown, the propeller is provided with three blades, but any suitable number 35 of blades may be employed.

Each blade is here shown as comprising a disk 3, and a radial arm 4. Each arm has a cylindrical inner portion 5, which fits and is adapted to turn in a radial opening 6 40 in the hub, and is also provided with an annular groove 7. The hub is provided in addition to the radial opening 6, with openings 8 which are parallel with the axis of the hub and each of which has a widened 45 rear portion 9 which communicates with one of the openings 6.

Bolts 10 are provided for adjustably securing the blades in place. Each bolt is provided with a substantially wedge-shaped 50 head 11 which fits in the widened portion of

one of the openings 8 and has a curved shoulder 12 on one side which is adapted to engage in the groove 7 of the arm of one of the blades. The blades may be turned to any desired angle or pitch and 55 when arranged at the desired angle, the nuts 13 are screwed up on the threaded stems 14 of the bolts, thereby causing the bolts to firmly lock the blades in place as will be understood.

Should a blade break or become injured, it may be readily removed and either repaired or replaced. Hence the propeller may be repaired without the necessity of 60 removing the same from the shaft.

By the construction of the propeller blades so that each comprises a disk and an arm, and also by the adjustable arrangement of the propellers with respect to the hub, the entire superficial area of each blade 70 is availed of as propelling surface, there is no twisted portion of any part of the propeller and the friction in the water is reduced to the minimum. My improved propeller may be made of any suitable material 75 and is exceedingly strong and durable.

Having described the invention, what is claimed is:

In a propeller, in combination with a hub having a substantially radial opening and 80 also having an opening at an angle to and communicating at one point with the first named opening, a blade having an arm arranged in the radial opening of the hub and adapted to turn therein to adjust the 85 blade to any desired pitch, and a locking bolt extending through said opening and having a widened wedge-shaped head presenting a curved shoulder at a point intermediate the ends of said bolt and which 90 shoulder engages the arm of the blade, and a nut screwed on said bolt at the end opposed to the shoulder, said nut bearing against the hub.

In testimony whereof I affix my signature 95 in presence of two witnesses.

HENRY D. ESTES.

Witnesses:

C. M. CROWE,
ROWAN HOLBROOK.
